GREGORY BRODSKY, OF LONDON, ONTARIO, CANADA, ASSIGNOR OF ONE-HALF TO THE CANADA VALVE & HYDRANT COMPANY, LTD., OF BRANTFORD, ONTARIO, CANADA, A CORPORATION OF ONTARIO

FOUR CORNER BOX STAYING MACHINE

Application filed December 18, 1926. Serial No. 155,672.

My invention relates to box making machines and has for its object to provide a machine that is adapted to simultaneously apply staying strips to all four corners of a box.

Such machines are commonly known as "quad", or "quadruple" staying machines and all prior machines of this type, as previously constructed have been extremely complicated, as a single prime mover, such as a rotating shaft, is employed to impart motion simultaneously to all four corner staying elements. The problem of applying power to the staying elements is further increased by the necessary adjustments of the elements to operate on boxes of different sizes and proportions.

According to the present invention, I provide an improved four corner staying machine that is characterized by its extreme simplicity in construction and effectiveness in operation. My invention represents a radical departure in machines of this type, due to the fact that separate power units are employed for actuating the staying units at each corner of the box, the power units being identical and interchangeable, thereby lending themselves readily to the adjustments necessary for staying boxes of different sizes and proportions. Each power unit also provides separate means for feeding the stay strip for the corresponding box corner, thereby further simplifying the structure, all as will hereinafter fully appear, with reference to the accompanying drawings, in which—

Fig. 1 is a view in side elevation of a machine embodying my invention, the stack of box blanks being removed.

Fig. 2 is a plan view of the parts shown in Fig. 1.

Fig. 3 is a view similar to Fig. 1, with the staying units removed to show the other parts.

Fig. 4 is a view in end elevation of the parts shown in Fig. 3, looking in the direction of the stack of box blanks.

Fig. 5 is a plan view of the box form showing the blank folders.

Fig. 6 is a vertical sectional view through the box form.

Fig. 7 is an enlarged view of the forward part of one of the staying units.

Fig. 7a is a fragmentary view showing some of the parts of Fig. 7 in a different position.

Fig. 8 is a horizontal sectional view on the line 8—8 of Fig. 7.

Fig. 9 is a vertical sectional view on the line 9—9 of Fig. 8.

Fig. 10 is a detail view of the latch device for the feed slide.

Fig. 11 is an enlarged sectional view showing the magnetic construction of a staying unit.

Fig. 12 is a diagrammatic view showing the electrical control for the staying units.

Like reference characters refer to like parts in the different figures.

Referring to Fig. 1, the machine provides an upwardly extending base or pedestal 1, upon which a pair of two armed brackets 2 and 3 are pivotally supported to turn about a central trunnion 4 supported by the base 1. The bracket 2 provides arms 2a extending in substantial alignment on opposite sides of the trunnion 4, while the bracket 3 provides similar arms 3a which extend substantially at right angles to the arms 2a, as shown in Fig. 2, although the angular relation between the arms 2a and 3a can be varied, as will be hereinafter described.

Each of the arms 2a and 3a terminates in a substantially horizontal flange portion 5, upon which is mounted a power unit, and inasmuch as all the power units are identical in construction, only one need be described in detail, with reference to Fig. 1 and to Fig. 7, which illustrates a unit, on an enlarged scale.

Each power unit consists of a casing 6 surrounding a solenoid or electromagnet 7 through which extends an armature in the form of a plunger 8. The plunger 8 is slidably supported in bearings 9 carried by the unit casing, and its outer end is surrounded by a spring 10 which holds the plunger retracted. The plunger 8 also carries a pressing element 11 which is adapted to be moved

toward the center of the machine when the magnet 7 is energized. Each pressing element 11 is provided with a vertical groove 12, the sides of which are substantially at right angles to each other, so that when plunger 8 is moved, the groove 12 of each pressing element 11 is adapted to register with a corner of a rectangular box form 13, as shown in its lowered position in Fig. 1.

As best shown in Figs. 3 and 4, the box form 13 is carried by a vertical shaft 14 slideable within the trunnion 4, and the lower end of the shaft provides a roller 15 which is in engagement with a cam 16 mounted on a shaft 17 extending at right angles to the box form shaft 14. The shaft 17 is journaled in the base 1, which provides an opening 18 for the cam 16, see Fig. 4, the shaft 17 extending beyond the base 1 and carrying a worm wheel 19. The worm wheel 19 is in mesh with a worm 20 carried on the shaft 21 of an electric motor 22, so that operation of the motor 22 is adapted to cause cam shaft 17 to turn at a considerably reduced speed. As shown in Fig. 3, the cam 16 is so formed that one revolution of the shaft 17 will cause the box form 13 to be raised to its dotted line position in Fig. 1 and remain there an appreciable time before it is lowered to the full line position of Fig. 3 at the completion of one revolution of the shaft 17.

As best shown in Figs. 2 and 3, a stack of box blanks 23 is supported in the angle between the pair of arms 2a and 3a by an arm 24 forming part of the base 1. The arm 24 provides a table portion 24a which is adapted to support the lowermost blank 23 substantially flush with the top of the box form 13 when the latter is in the lowermost position, and a push-off member 25, slideable in the arm 24a, is adapted to deliver the blanks 23, one by one, to the top of the box form 13. The push-off member 25 is adapted to receive a reciprocating motion, by reason of its connection to an oscillating lever 26, pivotally supported on a pin 27 extending through a slotted bracket 28. The lower end of the lever 26 is connected to one end of a plunger 29 by means of a link 30, the plunger being slidably mounted in a guide 31. The other end of the plunger 29 extends beneath the shaft 17 and carries a roller 29a in position to be engaged by a cam 32 carried by the shaft 17.

When the cam 32 engages the end of the plunger 29 it imparts a longitudinal movement thereto, which causes a movement of the push-off 25 in the direction of the box form 13. When the plunger 29 has reached the end of its stroke, the cam 32 leaves the plunger 29 and the plunger 29 is returned to its original position by means of a spring 33, which moves the plunger 29 to the right. The angular relation of the cams 16 and 32 on the shaft 17 is such that with the shaft 17 starting to rotate from

the position shown in Fig. 3, the push-off 25 completes its movement toward the box form 13 before the latter starts its upward movement. Consequently a box blank 23 is removed from the stack and positioned on the box form 13 at the beginning of each upward movement of the box form 13.

As the box form 13 is moved upwardly into the space between the four pressing elements 11 it carries a blank 23 into engagement with a set of folding fingers 34 supported just above the top of the box form 13 when it is in its lowered position, see Fig. 6. As shown in Fig. 5, the fingers 34 are carried on slotted bars 35 adjustably connected by pins 35a received in arms 36 extending diagonally inward from the presser unit supporting flanges 5. The slot and pin connection of the bars 35 permits the fingers 34 to be adjusted for folding blanks of different size. As the box form 13 carries a blank 23 upwardly, the sides 23a of the blank are engaged by the fingers 34 which serve to fold the sides downwardly as shown in Fig. 6. With this folding arrangement, the box form 13 reaches the upper limit of its movement with the sides 23a of the blank folded down and held in position for the attachment of the corner stays thereto by the pressing elements 11. As previously pointed out, the cam 16 is so formed that the box form 13, with the folded blank thereon, will remain in its upper position an appreciable time, during which the staying units operate to feed the stay material and affix it to the four corners of the box, as will now be described.

As best shown in Figs. 1 and 7, the plunger 8 of each staying unit is adapted to carry forward an upwardly extending bracket 37, at the end of which a feed roll 38 is rotatably mounted on a shaft 39. The bracket 37 provides an extension 40 at the end of which an idler roll 41 is rotatably supported, the function of the roll 41 being to hold the stay material 42 in engagement with the periphery of the feed roll 38. The guide roll 41 is loosely supported on the bracket extension 40 by means of a shaft 43 received in open slots 44, so that the roll 41, by reason of its weight, exerts just enough pressure to hold the stay strip 42 in engagement with the feed roll 38.

The feed roll 38 is adapted to be turned by means of a pulley 45, around which passes a cable 46, one end of which is connected to the pulley 45. The other end of the cable 46 is connected to a slide 47 vertically adjustable within a cylindrical casing 48 pivotally mounted on a pin 49 carried on a lug 50 extending from the magnet casing 6. The lower end of casing 48 carries a pivoted latch 51 received in a notch 52 provided in a stud 53 projecting from the plunger 8. With this connection it is apparent that when the plunger 8 is moved in the direction of the box form 13, the casing 48 will be turned about its pin

49 and the cable 46 acting on the pulley 45, will cause the feed roll 38 to be turned in a counterclockwise direction and thereby feed the stay strip 42 downwardly. The amount 5 of stay strip 42 which will be thus fed is determined by the angle through which the feed roll 38 is turned by the pulley 45, and this rotative movement is in turn dependent upon the position of the fixed end of the cable 10 46 on the casing 48. That is to say, for a given longitudinal movement of the plunger 8 the amount of stay strip fed simultaneously with this movement will be determined by the position of the slide 47 on the casing 48.

15 For purposes of illustration the vertical adjustment of the slide 47 is obtained by means of a threaded rod 54 extending through the slide 47, the end of the rod 54 extending outside the casing 48 and providing a head 20 55 whereby the rod 54 may be turned to shift the slide 47 vertically on the casing 48. Obviously this vertical adjustment of the slide 47 could be accomplished by means other than that shown for the purpose of changing the 25 position of the stationary point of attachment of the cable 46 with respect to the pulley 45. After the pulley 45 has been turned by the cable 46 to cause the roll 38 to feed the stay strip, the pulley 45 is returned to its original 30 position by means of a spring 56, surrounding the shaft 39 and acting on the pulley 45. However, this return movement of the pulley 45 is not imparted to the feed roll 38 for the 35 reason that a clutching device is interposed between the roll 38 and the pulley 45 which imparts the rotative movement of the pulley 45 to the roll 38, only when the pulley 45 is turned in a counterclockwise direction.

The one way clutch device between the pulley 45 and the roll 38 may be of any desired 40 type and is shown partially in Fig. 7 as consisting of a number of rollers 57 carried in pockets 58 in a cage 59 rotatable with the pulley 45. When the pulley 45 is turned in a 45 counterclockwise direction, the rollers 57 are forced in wedging engagement with the inner periphery of a rim 60 provided by the feed roll 38, so that rotation of the pulley is imparted to the roll 38. However, when the 50 pulley 45 is turned in a clockwise direction on its return no rotative movement is imparted to the roll 38 by reason of the fact that the rollers 57 are then free to bottom in the pockets 58.

55 As shown in Fig. 1, a supply of stay material 42 is carried by a reel 61 mounted on a bracket 62 which in turn is supported by the magnet casing 6. The strip material 42 is led from the reel 61 over an idler roll 63 60 which directs the material downward between the feed roll 38 and the pressure roll 41. The roll 63 is carried on an extension of the bracket 62 which also supports a box 64 within which is mounted a moistening roll 65 of any desired type. The roll 65 is so

mounted that its periphery is always partially engaged by the inner surface of the stay material 42, whereby the latter is moistened before it passes between the feed rolls. The box 64 may be supplied with either a 70 liquid adhesive or, when the strip material is already covered with adhesive, obviously water will suffice.

As previously pointed out, energization of any one of the solenoids 7 will cause the corresponding pressing element 11 to be moved toward a corner of the box form 13, and means are provided for carrying the bracket 37 with the feed roll 38 a predetermined distance toward the box form 13 when a plunger 8 is so moved. As best shown in Fig. 7, the bracket 37 provides a base 37a which is slidably mounted between guides 66 provided by the bearing 9. The base 37a provides a tail portion 67 carrying a pin 68 on which is mounted a collar 69 having a tooth 70. The tooth 70 is engaged by a resilient finger 71 carried by the pressing element 11, the head 71a of the finger 71 engaging the tooth 70 so that the bracket 37 is moved with the pressing element 11 when the parts are in the position shown in Fig. 7. A downwardly extending arm 72 is also mounted on the pin 68, so as to turn with the collar 69, and the weight of this arm 72 tends to hold the tooth 70 in engagement with the head 71a. The lower end of the arm 72 carries a set screw 73, the outer end of which is normally in engagement with a spring 74 extending downwardly and laterally from the portion 67, as 85 shown in Fig. 10.

With the parts in the position shown in Fig. 7, the forward movement of the finger 71 with the pressing element 11 initially causes the tooth 70 to turn slightly in a clockwise direction, but before the tooth 70 is disengaged from the head 71a of the finger 71, the set screw 73, turning on a much larger radius than the tooth 70 hits the portion 9a of the stationary bearing 9. Since the arm 72 and with it the tooth 70 can then turn no farther in a clockwise direction the continued movement of the presser element 11 is transmitted to the feed roll bracket 37 through the engaged tooth 70. As this combined movement continues the arm 72 is turned in a counterclockwise direction by the pressure of the stationary bearing portion 9a, until the tooth 70 cams down the head 71a to disengage itself therefrom, the finger 71 yielding downwardly to permit this. The parts then occupy the position shown in Fig. 7a. When this occurs, the pressing element will continue its movement toward the box form 13 to the end of its stroke, while the feed roll bracket 37 will remain stationary. As the feed roll 38 moves forward, the pulley 45 will cause it to feed a predetermined amount of strip material 42 downwardly into the notch 12 in the pressing element 11, 90 95 100 105 110 115 120 125 130

and as shown in Fig. 8, the strip is adapted to be fed downwardly through a V-shaped slot 75 in a knife plate 76. This plate 76 moves with the bracket 37, and when the plate 76 comes to rest with the bracket 37 the upper edge of the pressing element 11 will shear the strip 42 and carry the severed portion into engagement with the turned down edges of the box on the box form 13, thereby staying a corner. The plate 76 is caused to move with the bracket 37 by means of a pin 76a, a stud 93 received in a slot 94 in the plate 76 serving to keep the plate 76 parallel during its forward movement.

18 The outline of the groove 12 in the pressing element 11 is shown in dotted lines, Fig. 8, from which the cutting action of the forwardly moving pressing element 11 is quite clear. The dwell in the movement of the plate 76 insures that the strip material will not be moved when the cutting is taking place. Obviously the exact point in the stroke of the plunger 8 that the feed roll bracket 37 stops moving, can be determined by the position of the set screw 73 on the arm 72.

19 As previously pointed out, the casing 48 is turned about the pin 49 by reason of its connection to the stud 53 on the plunger 8, and this turning movement is also adapted to be arrested before the plunger 8 reaches the end of its stroke. When the plunger 8 moves to the left from the position in Fig. 7, the latch 51 automatically cams itself out of the notch 52, due to the fact that the pin 53 moves in a straight line while the latch 51 swings on the axis of the pivot pin 49, thereby stopping the feed of the strip material at substantially the same time that the bracket 37 stops its movement. On the return of the plunger 8 following the application of a stay strip, the latch 51 re-engages the notch 52 and is held therein by the spring 51a. On the return of the plunger 8 carrying the pressing element 11 the head 71a returns the feed roll bracket 37 to its original position by its engagement with the downward extending portion 67 of the feed roll bracket base 37a. This return movement of the base 37a is limited by stops on the guides 66, so that when the tail portion 67 can move no further the finger 71 yields downwardly and thus re-engages the tooth 70.

20 From the foregoing it is apparent that each time the motor 22 drives the shaft 17 through a complete revolution, a blank 23 is removed from the bottom of the stack and positioned on the top of the box form 13. Upon upward movement of the box form 13 the sides are folded down so as to present the four unstayed corners of the box to the pressing elements. The cam 16 is so formed as to hold the folded box in its upper position an appreciable length of time, during which the

pressing units are simultaneously energized to cause each element 11 to move toward a box corner, while a moistened strip is fed downwardly into the groove 12, severed, and carried forward into engagement with the corner of the box. Each staying unit is energized long enough to cause the stay strip to be applied with a sustained pressure, after which the units are de-energized.

21 As shown diagrammatically in Fig. 12, the several solenoid windings 7 are adapted to be energized when the box form 13 reaches its upward position and to be de-energized just before the box form 13 starts to move downwardly. The electrical control is shown as being effected by a contact disk 77 on the shaft 17, although obviously the control may be effected in other ways. (See Figs. 4, 12.)

22 Referring to Fig. 11, there is shown on an enlarged scale the detail construction of one of the power units in which the solenoid winding 7 is encased in a magnetic yoke 78. A laminated armature 79 is shown movable within the winding 7, the armature providing a head 80 which is normally held retracted within the bearing housing 9 by the spring 10. Thus the end of the armature 79 is separated from the core 81 by a space which is slightly more than the stroke of the plunger 8. When the winding 7 is energized the armature 79 is attracted to the core 81 to close the air gap and this movement of the armature 79 is imparted to the plunger 8 through non-magnetic plates 82 extending through the yoke 78 and secured to the plunger 8 by bolts 83. Obviously, modifications can be made in the exact structure of the power unit and the same results could be obtained by using a fluid or gaseous pressure medium and a piston to move the plunger 8.

23 In order to adjust the pressing units co-operating on boxes of different sizes and proportions, one pair of arms 2a and 3a are connected by an adjusting shaft 84, shown in Fig. 3. The shaft 84 is provided with oppositely threaded portions 85 in pivotal engagement with the arms 2a and 3a by means of threaded swivels 85a and 85b respectively so that by turning the shaft 84 by means of a handle 86, the two-armed brackets 2 and 3 can be pivotally moved about the trunnion 4 in either direction. This places the pressing units in different positions at the corners of a different size rectangle, whereby the pressing elements are adapted to operate on a box of that particular size. Obviously different box forms can be used as desired, and the casing 6 of each power unit is longitudinally adjustable on its supporting flange 5, by means of a pivot bolt 87 received in an elongated slot 88 in the flange 5. This permits the units to be adjusted independently with respect to the bracket arms 2a and 3a. As shown in Fig. 11 the pivot bolt 87 pro-

vides a head 87a seated in the presser unit casing 6, the threaded portion of the bolt 87 projecting beyond the slot 88 in the flange 5 to receive a nut 96. The nut 96 coacts with a washer 97 wider than the slot 88 to clamp the bolt 87 in any desired position within the slot 88, thereby fixing the presser unit casing 6 on the flange 5 in the direction of its axis. However, the casing 6 is adapted to turn on the pivot bolt 87 about a vertical axis when the brackets 2 and 3 are adjusted on the main vertical axis of the machine.

As shown in Fig. 3, the push-off member 25 which is adapted to feed the box blanks 15 over the box form 13, carries upwardly extending arms 89 which terminate in front of the blank stack in a finger 90. This finger 90 moves with the push-off 25 and is adapted to remove finished stayed boxes from above the box form 13 and cause them to move down a slide 91, thus clearing the completed boxes from the machine. Obviously, other means 20 may be employed for clearing the finished boxes from the machine without departing 25 from my invention.

When the box form 13 is moved downwardly following the staying of the corners of a box, the serrated folding fingers 34 shown in Fig. 6 hold the sides of the completed box 30 between them, as indicated in dotted lines so that the box form 13 in its lowered position is free to receive the next blank when it is delivered in a horizontal plane above the box form 13. Therefore when the box form with 35 a fresh blank thereon is again raised, the new blank forces the completed box between the fingers 34 upwardly, the fingers 34 offering no resistance to upward movement of the sides of the box. As the box form 13 reaches the 40 upper end of its stroke to complete the folding of the new blank, the completed box is loosely supported above the unstayed box, just folded, in a position to be in the path of movement of the clearing finger 90 as indicated in dotted lines in Fig. 3. Consequently 45 when the finger 90 again moves with the member 25 the completed box is pushed on to the slide 91 and so clears itself from the machine.

50 Referring again to Fig. 2 it will be seen that in order to insure automatically the relative angular position of all the staying units each pair of units is provided with a rigid connecting rod 92 slidably fitted into 55 a groove cut in the base of the unit casing, or otherwise attached to it, in such a manner as to make an angle of 45° with the unit's main axis. It is obvious that an adjustment of the brackets 2 and 3 will cause the units 60 to rotate on the pivot 87, but only relatively to the brackets. Substantially the units will always remain parallel to their original position, so that the sides of the vertical groove 12 in the pressing element 11 will invariably 65 register with the corner of the box form,

whatever the size, or proportion of the sides of the box may be.

I claim—

1. In a machine for applying stay strips to the four corners of a box, a pair of pivotally mounted brackets, each carrying opposed pressing elements operable by separate power units. 70

2. In a machine for applying stay strips to the four corners of a box, a pair of pivotally mounted brackets, each carrying opposed pressing elements operable by separate power units, and means for adjusting said brackets to position the pressing elements for operation on boxes of different dimensions. 75

15 3. In a machine for applying stay strips to the four corners of a box, a pair of pivotally mounted brackets, each carrying similar interchangeable power units providing opposed pressing elements operable on diagonally opposite corners of a box, and means for adjusting said brackets about their pivotal axis to position the pressing elements for operation on boxes of different dimensions. 80

20 4. In a machine for applying stay strips to the four corners of a box, a pair of pivotally mounted brackets, each carrying similar interchangeable power units providing opposed pressing elements operable on diagonally opposite corners of a box, means for adjusting said brackets about said pivotal axis, and means for adjusting said power units on said brackets whereby to adapt said pressing elements for operation on boxes of 85 different dimensions and proportions. 90

25 5. In a machine of the class described, the combination with a source of power, a pedestal, a box form vertically movable on said pedestal by said source of power, and brackets pivoted on said pedestal about an axis coinciding with that of the box form, of power units carried by said brackets, each providing a pressing element adapted to coincide with a corner of the box form when the latter is in its raised position. 100

30 6. In a machine of the class described, the combination with a source of power, a pedestal, a box form vertically movable on said pedestal by said source of power, and brackets pivoted on said pedestal about an axis coinciding with that of the box form, of power units carried by said brackets, each providing a pressing element movable toward a corner of said box form, and means for simultaneously operating said units to cause all of said pressing elements to engage the corners of the box form when the latter is in its upper position. 105

35 7. In a machine of the class described, the combination with a source of power, a pedestal, a box form vertically movable on said pedestal by said source of power, and brackets pivoted on said pedestal about an axis coinciding with that of the box form, of elec- 110

130

6

tromagnetic power units carried by said brackets, each providing a pressing element movable toward a corner of the box form, and means for simultaneously energizing all of said power units to cause said pressing elements to engage the corners of the box form when the latter is moved to its upper position by said source of power.

8. In a four corner box staying machine, 10 the combination with a source of power, a box form vertically movable from a lower to an upper position from said power source, means for removing the lowermost blank from a stack of flat box blanks and positioning it on said box form when the latter is in its lower position, and means for folding the sides of said box blank downwardly when said box form is moved into its upper position, of brackets pivotally supported about 15 the vertical axis of said box form, and power units carried by said brackets, each providing a pressing element adapted to engage a corner provided by the folded box blank when the box form is in its upper position.

25 9. In a machine of the class described, a power unit comprising a casing surrounding a solenoid winding, an armature extending longitudinally through said winding and normally retracted from the core of said winding by spring means, and a plunger coaxial with said armature carrying at its end a staying element, said plunger being connected to said armature by non-magnetic means whereby the motion of said armature is imparted to said plunger when the winding is energized.

10. In a four corner box staying machine, 40 the combination with a rotatably driven shaft, a base, a box form vertically movable on said base by the rotation of said shaft, and brackets adjustably mounted on said base and arranged symmetrically about an axis coinciding with that of the box form, of power units carried by and adjustable on said brackets, each providing a pressing element movable toward a corner of said box form, and means comprising a single actuating member carried by and rotatable with said shaft for simultaneously operating said units 45 to cause all of said pressing elements to move in unison to engage the corners of said box form, the said power units being adapted for adjustment on said brackets and said brackets being adapted for adjustment on 50 said base for operation of said pressing elements on box forms of different dimensions, without requiring adjustment of the operative connection between said actuating member and said power units.

60 GREGORY BRODSKY.
